(57) **CLAIM**

The ornamental design for a attachable wings for toy, as shown and described.

DESCRIPTION

FIG. 1 is a first perspective view of a attachable wings for toy showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a perspective view of the detachable wing of FIG. 1 with the wing in an rotation status;

FIG. 10 is a perspective view of the attachable wings for toy in a combined state; and,

FIG. 11 is a side view of the attachable wings for toy in a combined state.

The broken lines in the drawings depict portions of the attachable wings for toy that form no part of the claimed design.
